AUTOMATIC VOLTAGE CONTROL SYSTEM
FOR ALTERNATORSFenton F. Hutchinson, San Francisco, Calif., as-
signor to Kohler & Chase, San Francisco,
Calif., a corporation of California

Application December 10, 1941, Serial No. 422,346

4 Claims. (Cl. 171—119)

The invention, in general, relates to means for compensating for the voltage drop in a transmission or distribution line supplied by an alternator. More particularly, the invention relates to a combination of electrical units for maintaining a substantially constant voltage at the alternator, or at the terminals of the work circuit supplied thereby, regardless of load variations.

Considerable effort has been devoted in recent years by those skilled in the art toward the provision of means and methods for increasing the efficiency of alternators and towards the elimination or reduction of excessive wear upon the various electrical units and parts of an alternating current generating system. One of the more difficult problems encountered in practically all of such systems is that of compensating for the drop in voltage in the work circuit under varying resistance-reactance loads. While some measure of success has been attained in the solution of this problem where only resistance loads are connected into the work circuit, or under load conditions wherein the power factor is substantially unity or does not vary appreciably, there has been but indifferent success in maintaining a substantially constant voltage at the terminals of the work circuit where wide variations in power factor occur and where varying inductive loads are connected therein. In nearly all of the recently developed systems that have performed their intended functions with any degree of success, a constant supervision of the system and the presence of attendants is required for adjusting commutator brushes or the commutating plane, adjusting tap points on transformers, or the substitution of transformer coils to meet the varying load conditions, and this is especially true in such systems wherein the power factor variation extends beyond predetermined limits for which the system has been constructed. The present invention is directed to obviating the foregoing and other difficulties encountered in alternating current generating systems under all conditions of load, and particularly where the load consists of variable inductances.

A primary object of my invention is to provide an alternating current generating system affording automatic regulating means for compensating for the voltage drop in an alternating current work circuit due to the connection thereto of variable resistance-reactance loads, and regardless of the power factor value of the work circuit.

Another object of the present invention is to provide a system of the aforementioned character which does not require the shifting of the commutator plane of any unit, and which does not require supervision or the presence of an attendant.

A still further object of the invention is to pro-

vide an improved system of the indicated nature which is additionally characterized by a minimum of electrical units.

Another object of my invention is to provide an improved alternating current generating system in which no arcing at commutator brushes occurs, and undue wear upon brushes and commutator segments is avoided.

The foregoing and other objects are attained in a preferred embodiment of my invention which is diagrammatically illustrated in the accompanying drawing. It is to be understood that while the accompanying drawing depicts a preferred embodiment for single phase operations, the invention is suitable for adaptation in embodiments operating in poly-phase as well, and it also is to be understood that I am not to be limited to the precise embodiment shown, nor to the precise arrangements of the several units thereof, as my invention, as defined in the appended claims, can be embodied in a plurality and variety of forms.

Referring to the drawing:

The single view is a schematic showing of the various electrical units and circuits of a preferred embodiment of my invention, as exemplified in a system operating in single phase.

In its preferred form, the automatic voltage control system for alternators of my invention preferably comprises, in combination with an alternator, an exciter for supplying the field of the alternator with direct current of varying magnitude; said exciter including an auxiliary field, together with means for deriving a variable potential from the work circuit supplied by the alternator, and means for rectifying the derived, variable potential and applying the rectified, derived potential to the auxiliary field of said exciter whereby the exciter variably excites the field of the alternator.

As illustrated in the accompanying drawing, my improved automatic voltage control system for alternators consists of but four electrical units, with their attendant leads and parts, inclusive of the alternator, which is designated in the drawing generally by the reference numeral 11. In addition to the alternator, the system includes a specially wound exciter 12 for supplying a direct current of varying magnitude to the field of the alternator 11; a specially wound current transformer 13 for deriving a variable potential from the circuit supplied by the alternator 11; and a specially constructed direct current generator or converter 14 for rectifying the variable potential derived from the alternator 11 work circuit and for applying the rectified, derived potential to the auxiliary field of the exciter 12, so that the exciter in turn will furnish a direct current of variable magnitude to the field of the alternator 11. This system, as hereinabove generally described, has been successfully em-

ployed in automatically maintaining a substantially constant voltage at an alternator, or at the terminals of the work circuit supplied thereby, under variable resistance-reactance loads and regardless of the power factor value of the work circuit of the alternator.

For convenience of illustration and explanation only, I have depicted in the accompanying drawing an alternator 11 of a type having four field poles 16, 17, 18 and 19 arranged in opposed pairs, each pole carrying a single winding or main field coil 21, 22, 23 and 24, respectively. It is of course to be understood that the present invention can be embodied in alternators having any desired number of pairs of field poles, and that the armature of the alternator can be wound for either single phase or polyphase operations. Moreover, it is clear that it is optional whether the alternator armature be mounted for rotation about fixed poles, or whether the field poles be arranged for rotation about a fixed armature. In the embodiment of the invention illustrated, the alternator 11 comprises fixed field poles with its armature mounted for rotation about the poles upon a driven shaft 25. As is customary, the current produced by the alternator may be collected by suitable brushes 26 and 27 bearing upon collector rings 28 and 29, respectively, to which the terminals of the alternator armature winding are fastened; the collector rings being connected to but insulated from the armature shaft 25. The work or load circuit supplied by the alternator 11, under single phase operation, includes two trunks or mains 31 and 32 leading from the brushes 26 and 27, respectively.

The fields of the alternator 11 are supplied with direct current from the specially wound exciter 12 which may be of a type which includes four field poles 36, 37, 38 and 39 each of which carries a main field coil 41, 42, 43 and 44, respectively, together with shunt windings 46, 47, 48 and 49, respectively. A suitable resistance, not shown, may be connected into the exciter shunt circuit for regulating the exciter. In addition to the indicated shunt and series or main field windings, each of the field poles 36 to 39, inclusive, is provided with an auxiliary field coil 51, 52, 53 and 54, respectively and such coils are wound in directions opposite to the series and shunt windings and, hence, are of opposite polarity thereto. While the armature of the exciter 12 may, if desired, be mounted on shaft 25 upon which the alternator armature is mounted, the exciter armature nevertheless can be secured to a separate driven shaft 55 with equivalent results. In view of the connections, as shown, direct current flows from the exciter commutator brush 56 through a lead 57 connected to alternator field coil 21, thence through the several alternator fields; thence through a lead 58 connecting alternator field coil 24 to the series windings of the exciter; thence back to exciter commutator brush 59 through a lead 60 from main exciter field coil 44 to complete the circuit. Since the auxiliary field coils of the exciter 12 are of opposite polarity to the shunt and series windings, it will be appreciated that, with the armature of the exciter rotating at a constant R. P. M. and a predetermined current flowing in all of the fields of the exciter at no load, the exciter will supply to the fields of the alternator 11 a substantially constant voltage direct current whereby the alternator will produce an alternating current having a predetermined, constant voltage at no load. Moreover, the relationship be-

tween the auxiliary field coils of the exciter, on the one hand, and the shunt and series windings thereof, on the other hand, is such that variations from the predetermined value of current flowing in the auxiliary field coils of the exciter, as a result of load variations in the work circuit supplied by the alternator and of the combination of electrical units of my present improved system, are balanced by corresponding or proportional variations in the current flowing in the shunt and series windings of the exciter; and this balance is always maintained regardless of the type of load connected into the work circuit and regardless of the power factor characteristics of such work circuit. As a result of the maintenance of this balance in the exciter 12, voltage variations in the alternator work circuit are automatically compensated for, and the voltage on the alternator or at the terminals of its work circuit, is maintained substantially constant at the predetermined no load value. As is well understood, the foregoing applies both to flat-compounding and over-compounding, the only difference between the latter and the former being that once a definite value of over-compounding has been decided upon it is only necessary to wind the exciter coils as well as the coils of transformer 13 initially to effect such value of over-compounding. Once such coils are wound for either flat or over-compounding, there need not be any alternation thereof whatsoever for a given capacity of alternator.

As illustrated in the accompanying drawing, my improved system includes a specially wound current transformer 13 comprising a saturated leg with an iron shunt including an air gap between an input or primary coil 61 and an output or secondary coil 62. As shown, the input 61 of transformer 13 is connected across the work circuit supplied by the alternator 11 by means of a pair of leads 63 and 64, while the terminals of the output 62 of transformer 13 are connected to leads 66 and 67 which are connected to the fields of regulator 14 as hereinafter described. It is clear that since the input or primary 61 of transformer 13 is always across the load circuit, the current flowing in transformer 13 under no load conditions is entirely magnetizing current which produces an E. M. F. in the output or secondary 62 that is always in direct proportion to the voltage of input 61. It also is clear that this construction of transformer 13, as thus far described, imposes a definite limit to the current which may be withdrawn from the secondary 62 so that any attempt to withdraw current in excess of such limit merely results in the terminal voltage dropping to such an extent that only limited current flows therefrom. Hence, since the output of transformer 13 supplies the fields of regulator 14 and the latter, in turn, feeds the auxiliary fields of exciter 12, the current flowing in said auxiliary fields of the exciter under no load conditions will have a predetermined value and is just sufficient, with respect to the current flowing in the shunt and series windings of the exciter, with its armature moving at a constant R. P. M., to maintain the direct current produced by the exciter at substantially a constant voltage and, as a result, the alternator voltage is maintained substantially constant at a predetermined value at no load. In accordance with my invention, the current transformer 13 is provided with an additional or tertiary coil 68 which is disposed on the saturated leg of the transformer between its input 61 and its output

62. Moreover, the tertiary coil 68 is connected in series with the load and with the alternator 11 by means of the leads 69 and 70, as shown. As a result of the disposition of tertiary coil 68 on the saturated leg of transformer 13, as shown, and of the foregoing connections thereof into the load and alternator circuit, the amount of current flowing in the tertiary 68 will have a direct influence upon the magnitude and phase of the current appearing at the terminals of the output 10 62 of the transformer.

As indicated above, my improved system includes means for utilizing the variable potential derived from the work circuit by transformer 13 for variably exciting the auxiliary fields of the exciter 12, whereby the fields of the alternator 11 are supplied with direct current of variable magnitude in direct response to load variations. These means preferably include a specially constructed direct current generator or regulator 14, the fields of which are supplied with alternating current of variable potential from the output 62 of current transformer 13 through the leads 66 and 67; together with means for rectifying the derived potential and applying the same as a rectified, pulsating direct current to the auxiliary coils 51 to 54 inclusive of the exciter 12. As schematically shown at the left center of the drawing, the regulator 14 includes a corresponding number of pairs of field poles as the alternator 11, which in the present embodiment is two pairs or four poles; such field poles of the regulator 14 being designated generally by the reference numerals 76, 77, 78 and 79. Each of these field poles is wound with a single main field coil 81, 82, 83 and 84, respectively, which are connected in circuit with the output 62 of the transformer through the leads 66 and 67, as shown. The field poles of the regulator are spaced equidistantly apart around the regulator armature, and the faces of the field pole pieces are formed of equal length so that there are defined four equal air gaps or spaces around the armature. In the preferred construction of regulator, the faces of the field poles are made to such length each that each of the four defined air gaps between the faces are approximately two-thirds the length of a field pole face and these dimensions, as well as the lengths of the field pole faces, are critical. The generator 14, moreover, is preferably provided with an armature winding which is divided generally into four distinct and separate coils, designated by the numerals 86, 87, 88 and 89, and each of these armature coils is preferably equal to the dimensions of a field pole face; such dimensions also being critical. The armature of regulator 14 is preferably mounted upon shaft 25 upon which the alternator armature is mounted although, if desired, such regulator armature may be mounted on a separate shaft 90 so long as such shaft is driven synchronously with shaft 25. In accordance with my invention, the output voltage of the regulator 14, as conditioned by transformer 13, is rectified and applied to vary the excitation of the auxiliary field coils of the exciter 12. To this end, the terminals of the armature coils 86 to 89 inclusive of the regulator are connected preferably to eight segments of a rectifying commutator 91, the commutator segments being electrically connected together in alternate pairs so as to make practically a two-part commutator. The rectifying commutator 91 is mounted on shaft 90 and the voltage, as thus modified, is taken off the 70

commutator 91 by brushes 92 and 93, bearings thereon, to appear rectified as a pulsating direct current voltage applied to the leads 94 and 95 connected to the brushes 92 and 93, respectively; such direct current voltage being of variable magnitude and phase depending upon the magnitude and phase of the load. As shown, the rectified current of variable potential produced by the regulator or converter 14 is supplied directly to the auxiliary field coils 51 to 54 inclusive, and to this end the several auxiliary coils are connected together by means of the leads 96, 97 and 98, and the lead 94 is connected to auxiliary field coil 54 while the auxiliary field coil 51 is connected to lead 95 connecting to brush 93 of the regulator commutator, to complete the circuit.

The effect upon the fields of the regulator 14 of the disposition of tertiary coil 68 between the input and output of transformer 13, and of connecting such tertiary coil in series with the load and with the alternator depends, of course, upon the presence or non-presence of a load in the work circuit of the alternator. Moreover, the effect of the specially constructed regulator upon the auxiliary fields of the exciter depends upon the presence or non-presence of a load in the alternator work circuit. Under no load conditions, the E. M. F. produced at the terminals of the output 62 of the transformer 13 is in direct proportion to the voltage of the transformer input 61, since the latter is always across the work circuit. Moreover, the voltage at rectifying commutator 91 of the regulator 14, under no load conditions, is such that the produced current of the regulator, which is fed to the auxiliary field coils of the exciter, is always sufficient to maintain the correct or predetermined voltage on the exciter. It may be observed here that when maximum voltage appears at the commutator of the exciter 12, minimum current flows in the exciter series and shunt windings and maximum current flows in the auxiliary field coils 51 and 54 inclusive so that the correct voltage is produced and this voltage balance is maintained so long as there is no change of potential in the work circuit supplied by the alternator. However, when the voltage applied to the fields 81 to 84 inclusive of the regulator drops, as a result of a load being connected into the alternator work circuit, the bucking potential at rectifying commutator 91 also drops, and the current flowing to and in the auxiliary field coils 51 to 54 inclusive of the exciter is reduced thereby permitting an increased current to flow in the series and shunt windings of the exciter. Consequently, the exciter will produce promptly the needed current to feed the alternator fields and bring the voltage of the alternator to its no load value. Clearly, when the load is removed from the alternator work circuit, the reverse of the above occurs, in that the terminal voltage of the transformer output rises which, in turn, increases the field strength of the regulator so that the produced current of the regulator is increased and an increased current flows in the auxiliary field coils of the exciter, with a corresponding decreased current flow in the series and shunt windings thereof, thus maintaining the balance or relationship therebetween. It will be understood from the drawing that the automatic variable excitation of the auxiliary field coils of the exciter 12 by the produced direct current of variable potential supplied from regulator 14 is similar whether the load connected into the alternator work circuit is a pure resist-

ance, a pure inductance, or a combination of these types of loads. Due to the special construction of the regulator 14 with its armature winding concentrated as shown and each of the four divisions of such armature winding equal in dimension to a field pole face, as well as the disposition of the tertiary 68 of the transformer 13 between its input and its output, the regulator 14 so functions that as the power factor characteristics of the work circuit approaches unity the current produced by the regulator 14 increases, and as the power factor of the load circuit decreases, the produced current of the regulator decreases.

As indicated above, the present improvement is entirely suitable for poly-phase operations with but slight changes in connections. In a three-phase system, for example, the transformer 13 would be duplicated and connections made for the alternator circuit thereto corresponding to the connections for single phase in that the inputs of the two transformers would be connected across the three-legs of the alternator work circuit, and the tertiary coils of the two transformers would be connected in series with the load as well as the armature by suitable leads to two brushes on the alternator collector rings. Of course, the alternator armature would be wound in three-phase rather than single phase but it would not be necessary to wind the regulator armature for three-phase and the armature winding of regulator 14 could be used without change. The two transformer outputs would be coupled together and connected in circuit with the regulator field or, if desired, two fields of two poles of the regulator 14 could be connected to one transformer output and the other two fields connected to the other transformer output.

An important advantage of my present improved system over standard or conventional alternating current generator circuits is that the commutating plane of the converter 14 is perfect when the converter is producing its maximum current in its armature circuit. Consequently, any lowering of the current in the armature circuit due to a weakening of the converter field strength, has no appreciable effect upon the commutator plane and no arcing at the commutator brushes 92 and 93, or wearing of the segments of the commutator occurs. Moreover, the commutator brushes are not required to be adjusted and no supervision of any kind is required. Another important feature of this improved system is that no re-winding or rematching of transformer coils is required nor any transformer tap adjustments, for the system operates automatically to compensate for variations of potential in the work circuit supplied by the alternator regardless of the type of load that may be connected therein up to the maximum capacity of the alternator.

It is to be understood that the appended claims are to be accorded a range of equivalents commensurate in scope with the advance made over the prior art.

I claim:

1. An automatic voltage control system for alternators comprising, in combination with an alternator, an exciter for supplying the field of the alternator with direct current of variable magnitude; said exciter including shunt and series field windings as well as an auxiliary field coil of opposite polarity to the polarity of said shunt and series windings; said series field winding of said exciter being connected in series-

5 circuit relation with the field of the alternator and with the exciter armature winding, means for deriving a variable potential from the work circuit supplied by the alternator, a regulator 10 the field of which is electrically connected to said means, and a rectifying commutator on the shaft of said regulator for rectifying the derived, variable potential obtained from the alternator work circuit by said means and for reducing the field strength of said exciter by applying the rectified, derived potential as a pulsating direct current of variable magnitude to said auxiliary field coil of said exciter.

2. An automatic voltage control system for alternators, said system comprising, in combination with an alternator and a work circuit supplied thereby, an exciter including shunt and series field windings as well as an auxiliary field of opposite polarity to the polarity of said shunt and series windings; said series field winding 15 of said exciter being connected in series-circuit relation with the field of the alternator and with the exciter armature winding, a current transformer including an input coil connected across the work circuit supplied by the alternator, an output coil, and a tertiary coil between said input and output coils, means connecting said tertiary coil in series with a load in the work circuit as well as with the alternator whereby 20 the output potential of said transformer output coil is modified directly in response to variations of load in the work circuit supplied by the alternator, a regulator the field of which is connected to said output coil for receiving alternating current of variable magnitude therefrom, and means 25 in said regulator connected to said auxiliary field of said exciter for rectifying the alternating current of variable magnitude derived from the alternator work circuit by said current transformer and for reducing the field strength of said exciter by applying the same as a rectified, pulsating direct current of variable magnitude to said auxiliary field.

3. In an automatic voltage control system for alternators, the combination of an exciter including an auxiliary field for supplying direct current of variable magnitude to the field of an alternator, and a regulator including a rectifying commutator for supplying a pulsating direct current of variable magnitude to said auxiliary field of said exciter; said regulator including two pairs of opposed field poles the faces of which are of predetermined length and dimensions, said poles being spaced equidistantly apart about the armature of said regulator to provide equal spaces therebetween; each of said spaces being two-thirds the length of the face of a field pole, and a concentrated armature winding on the armature of said regulator divided into four separate coils each of which has a dimension substantially 30 equal to the dimension of a field pole face; said four armature coils being spaced equidistantly apart on the regulator armature.

4. A regulator for an alternator, said regulator comprising a rectifying commutator consisting of a pair of opposed field poles having faces of predetermined area; said field poles being arranged so as to provide equal spaces therebetween each of which is approximately two-thirds the length of a field pole face, an armature, and an armature winding on said armature divided into separate coils equidistantly spaced apart and each of which has a length approximately equal to the length of a field pole face.

FENTON F. HUTCHINSON.
